UNITED STATES PATENT OFFICE.

WILLIAM O. KENNINGTON, OF DETROIT, MICHIGAN, ASSIGNOR TO REMY ELECTRIC COMPANY, OF ANDERSON, INDIANA, A CORPORATION OF INDIANA.

CIRCUIT-BREAKER AND DISTRIBUTER UNIT.

1,265,918.

Specification of Letters Patent. Patented May 14, 1918.

Application filed April 14, 1916. Serial No. 91,056.

To all whom it may concern:

Be it known that I, WILLIAM O. KENNINGTON, a subject of the King of Great Britain, residing at Detroit, in the county 5 of Wayne and State of Michigan, have invented a certain new and useful Improvement in Circuit-Breakers and Distributer Units, of which the following is a full, clear and exact description.

- 10 This invention relates to ignition apparatus, and particularly to means for mounting and rotating the circuit breaker cam and distributer segment of a combined circuit breaker and distributer unit, the object of 15 the invention being to provide means whereby the cam and distributer are maintained at all times in proper relative angular positions and to so mount and secure the parts on the shaft that the cam and segment can 20 be very easily and properly positioned with respect to the parts of the engine. A further object is to accomplish these results by a construction which is simple and inexpensive but durable and highly efficient.
- 25 The invention may be briefly summarized as consisting in certain novel details of construction and combination and arrangements of parts which will be described in the specification and set forth in the appended claims.
- 30 In the accompanying sheet of drawings, wherein I have shown the preferred embodiment of my invention, Figure 1 is a sectional view through a circuit breaker and distributer unit, parts being shown in elevation, 35 the section being taken substantially along the irregular line 1—1 of Fig. 2; Fig. 2 is a top plan view with the distributer cap removed; and Fig. 3 is a detail view on a slightly enlarged scale, showing the cam and distributer segment in section and the shaft in elevation.

Referring now to the drawings, 10 represents the circuit breaker casing and 11 the distributer cap which is mounted on the casing and which may be secured thereto by any suitable means. Although the particular form and arrangement of the contacts or contact members of the circuit breaker is immaterial to the present invention, I 45 have here shown a construction which includes a breaker plate 12 suitably supporting a stationary contact 13 adapted to be

engaged by a contact carried by a pivoted breaker lever 14 supported by the breaker plate 12.

55

Extending into the casing 10, through the bottom thereof, is a shaft 15 which rotates the circuit breaker cam and distributer segment to be referred to presently. It will be observed that this shaft is provided with a 60 tapered or conical portion 15^a, a threaded portion 15^b located just above the tapered portion 15^a, and an end portion 15^c which is preferably cylindrical, the cylindrical end 15^c of the shaft being located just above 65 the threaded portion 15^b.

At 16 is shown a circuit breaker cam which in this case is a four-point cam designed for a four cylinder engine, although it is to be understood, of course, that the number of 70 cam points or projections may be greater or less than four, the number depending upon the number of cylinders of the engine. This cam is provided with a central conical opening which fits onto the tapered or conical 75 portion 15^a of the shaft 15, and it is securely clamped thereto by a nut 17 engaging the threaded portion 15^b of the shaft. In this manner the cam is held to the shaft without any danger of slipping, and at the same 80 time the cam can be accurately adjusted and then permanently positioned relative to the drive shaft and the parts of the engine.

Above the cam is a distributer segment 18 which, in accordance with another feature of 85 my invention, is positively driven by the cam. This segment is provided with a socket containing a metal cup-shaped bushing 18^a which receives with a close but not necessarily driving fit the cylindrical end portion 90 15^c of the shaft 15. The segment is positively driven by the cam through the medium of a pin 19 which is fixed to and projects up from the cam and extends or enters into a suitable socket or opening provided in the segment. The segment has slip connections with both the ends of the shaft and the pin, so that it can be removed when desired.

95 After the apparatus has been attached to 100 the engine the proper time of break and the connection of the distributer to the proper cylinder are obtained by loosening the nut and cam and by turning the cam into the

position corresponding to the position of the parts of the engine as will be readily understood by those experienced in fitting and adjusting ignition apparatus to engines.

- 5 When the cam is in the proper position, the nut will be tightened, whereupon the cam is permanently secured in its proper position. By having the distributor positively associated with and driven by the cam any variation in position of the cam relative to the driving shaft which may be made when adjusting the apparatus to the engine, produces a corresponding variation of the distributor segment. In consequence the interrupter and distributor are thus properly synchronized with each other.

The cam is preferably made from stock of polygonal cross-section, either squared, hexagonal, octagonal or in any shape, depending upon the number of cylinders of the engine, by placing the stock in a lathe or similar machine and rounding off the edges. In this manner a cam of suitable contour is produced very cheaply.

- 25 The distributor segment is preferably composed of a body 18^b of insulating material such as bakelite, on the upper part or surface of which is secured a distributing strip or plate 18^c of good conducting material having one end extending beyond the insulating body 18^b and adapted to rotate in the usual manner in proximity to a plurality of stationary distributor terminals, one of which is shown at 18^d. The plate or strip 35 18^c carries a yieldable contact member 18^e which is adapted to engage the central terminal 18^f of the distributor.

Additionally, the segment here shown is provided with a safety spark gap feature. 40 This gap is formed between two points, one on the upper strip or plate 18^c and the other at one end 18^g of a plate 18^h molded in the lower part of the segment and grounded on the shaft. Of course, this spark gap does 45 not normally carry sparks but should the secondary circuit to one or more of the spark plugs become disconnected, the spark will jump across this gap, thereby relieving the coil which is associated with the distributor of excessive electrical stresses.

It is to be understood, however, that the cam may be formed by some other process than explained above, and the details of construction of the segment may be other than 55 here shown, the most important or essential features of the present invention being the means described or equivalent means for holding or securing the cam on the shaft and the relative arrangement of the cam and segment and manner of mounting and driving the latter.

Having thus described my invention, what I claim is:

1. In a circuit breaker, a pair of relatively movable contacts, a cam for shifting one of

the contacts, a shaft by which the cam is supported and rotated, the said shaft being formed or provided with a conical seat or bearing for the cam, and axially adjustable means engaging with the shaft for binding 70 the cam in firm engagement with its tapered seat, whereby the cam by the release of such means may be angularly adjusted with respect to the shaft and then secured thereto in any adjusted position.

2. In a circuit breaker and distributor unit, a pair of relatively movable contacts, a cam for operating the same, a rotary shaft carrying and supporting the cam, and having a conical portion constituting a seat for the cam, axially movable means engaging the shaft and adapted to force the cam down in any angularly adjusted position it may occupy firmly upon its conical seat, and a distributor segment adapted to be rotated 80 with the cam in fixed angular relation thereto.

3. In a circuit breaker and distributor unit, a pair of relatively movable contacts, a cam for operating or controlling the same, a 90 rotary shaft carrying the same and having a conical portion constituting a seat for the same. Means for forcing the cam in any angular position it may occupy with respect to the shaft upon its conical seat, and a distributor segment having a rigid driving connection with the cam.

4. In a circuit breaker and distributor unit, a pair of relatively movable circuit controlling contacts, a cam for operating the 100 same, a shaft having a conical portion forming a seat for the same, a nut engaging with the shaft above the conical cam seat adapted to force the cam down upon its seat, and a distributor segment having a socket to receive the end of the shaft, said cam being rigidly connected with the segment whereby said segment is driven by the cam.

5. In a circuit breaker and distributor unit, a cam for controlling the same, a shaft 110 having a conical portion forming a seat thereon for said cam, and a threaded portion adjacent the conical seat, a nut engaging the threaded portion for forcing the cam down into firm union with its seat, a distributor segment having a socket for the end of the shaft and a driving pin between the cam and the segment and constituting the means by which the cam rotates the segment.

6. In a distributor, a casing having a central terminal, a shaft projecting into the casing, a distributor segment mounted on the shaft, a conducting plate carried by the segment and electrically connected to the central terminal, a second plate carried by the segment and grounded on the shaft, said plates having a pair of points constituting a safety spark gap.

7. In a distributor, a casing having a centrally disposed terminal, a distributor seg-

ment comprising a body of insulating material mounted on the shaft and provided on opposite sides with two plates, one of said plates being insulated from the shaft and electrically connected to the central terminal, the other plate being grounded on the shaft and spaced from the first named plate, said plates having a pair of oppositely

disposed portions constituting a safety spark gap. 10

In testimony whereof, I hereunto affix my signature in the presence of two witnesses,

WILLIAM O. KENNINGTON,

Witnesses:

F. P. McDERMOTT, Jr.,

A. E. BERDON.
